[57] CLAIM

The ornamental design for a handle for an exercise apparatus, as shown and described.

DESCRIPTION

FIG. 1 is a rear perspective view of a handle for an exercise apparatus showing our new design;

FIG. 2 is a right side elevational view thereof;

FIG. 3 is a left side elevational view thereof;

FIG. 4 is a first front elevational view thereof;

FIG. 5 is a rear elevational view thereof;

FIG. 6 is a top plan view thereof;

FIG. 7 is a first bottom plan view thereof;

FIG. 8 is a second front elevational view thereof; and,

FIG. 9 is a second bottom plan view thereof.

The broken lines are for illustrative purposes only and form no part of the claimed design.
